US00D902539S

(12) **United States Design Patent** (10) **Patent No.:** **US D902,539 S**
(45) **Date of Patent:** **** Nov. 24, 2020**

(54) **SHOE** 3,629,051 A 12/1971 Mitchell
D237,323 S 10/1975 Inohara
(71) Applicant: **PUMA SE**, Herzogenaurach (DE) D244,967 S 7/1977 Famolare, Jr.
4,089,069 A 5/1978 Vistins
(72) Inventor: **Thomas Mace**, Nuremberg (DE) D263,348 S 3/1982 Cohen
D263,518 S 3/1982 Cohen
D265,019 S 6/1982 Vermonet
(73) Assignee: **PUMA SE**, Herzogenaurach (DE) 4,345,387 A 8/1982 Daswick
4,378,641 A 4/1983 Tarlow
D297,682 S 9/1988 Le
D305,278 S 1/1990 Kiyosawa
D306,372 S 3/1990 Diaz et al.
(**) Term: **15 Years** D307,971 S 5/1990 Maccano et al.
(21) Appl. No.: **29/669,705** D319,337 S 8/1991 Hatfield
(22) Filed: **Nov. 9, 2018** D321,973 S 12/1991 Hatfield
D323,059 S 1/1992 Hatfield
D327,164 S 6/1992 Hatfield
D327,976 S 7/1992 Biotteau
D329,528 S 9/1992 Hatfield
D334,279 S 3/1993 Teague
D340,797 S 11/1993 Pallera et al.
D350,222 S 9/1994 Hase
D353,708 S 12/1994 Crowley, II
D353,935 S 1/1995 Pollack
D356,438 S 3/1995 Opie et al.
(51) **LOC (12) Cl.** 02-04 D357,347 S 4/1995 Leick

CLAIM

The ornamental design for a shoe, as shown and described.

DESCRIPTION

FIG. 1 is a top, front, and right perspective view of an ornamental design for a shoe;

FIG. 2 is a front elevational view of the shoe of FIG. 1;

FIG. 3 is a rear elevational view of the shoe of FIG. 1;

FIG. 4 is a left side elevational view of the shoe of FIG. 1;

FIG. 5 is a right side elevational view of the shoe of FIG. 1;

FIG. 6 is a top plan view of the shoe of FIG. 1; and,

FIG. 7 is a bottom plan view of the shoe of FIG. 1.

The dash-dash-dash broken lines are included for the purpose of illustrating portions that form no part of the claimed design.
